Primary Examiner — Cynthia M. Chin(74) *Attorney, Agent, or Firm* — Andrus Intellectual Property Law, LLP**CLAIM**

The ornamental design for a remote control for marine propulsion system, as shown and described.

DESCRIPTION

FIG. 1 is a rear perspective view of a remote control for a marine propulsion system according to our new and ornamental design;

FIG. 2 is a side view thereof;

FIG. 3 is an opposite side view thereof;

FIG. 4 is a rear view thereof;

FIG. 5 is a front view thereof;

FIG. 6 is a top view thereof; and,

FIG. 7 is a bottom view thereof.

The broken lines illustrate the aspects of the remote control for a marine propulsion system that are not part of the claimed design.
